UNITED STATES PATENT OFFICE

RALPH E. PAGE, OF BINGHAMTON, NEW YORK, ASSIGNOR TO THE TABULATING MACHINE COMPANY, OF ENDICOTT, NEW YORK, A CORPORATION OF NEW JERSEY

PAPER FEEDING DEVICE FOR TABULATING MACHINES

Application filed December 24, 1925. Serial No. 77,643.

This invention covers improved platen feed devices for tabulating machines or the like.

It is customary in machines of that type to print data on sheets of paper carried by a platen actuated by mechanism, such as a ratchet device, which gives the platen a step-by-step rotation in order that each item or line of data may be printed one ordinary line space below the preceding item. If an extra wide space is desired for any purpose, as for instance, before printing a total it has been customary to obtain that extra space by actuating the regular ratchet device more than once between successive printing operations.

15 The present invention discloses a device by means of which an increased line space may be obtained by a single actuation of the paper feeding mechanism.

In certain kinds of work, as for instance 20 in printing certain information direct from a record card onto an order blank or bill, a space between lines is required equal to the length of the order blank or bill, and the principal object of this invention is to provide means suitable for feeding the paper under such conditions.

For purpose of illustration my invention is shown in connection with a printing tabulating machine of well known type, such as 30 is shown in the copending application of Clair D. Lake, Serial No. 639,153, filed May 15, 1923, but it should be understood that the invention may be used on any other machine of like nature and the invention extends to 35 such use.

In the drawings,

Fig. 1 is a side view of my device, portions 40 of the tabulating machine frame and printing mechanism being indicated by dotted lines.

Fig. 2 is a plan view of Fig. 1.

Fig. 3 is an enlarged detail view on line 3—3 of Fig. 2.

45 Fig. 4 is a detail view, partly in section, on line 4—4 of Fig. 3.

Fig. 5 is an enlarged view of upper end of rack with stop cam.

50 In Fig. 1, 10 is the total print cam and 11 is the listing cam of the tabulating machine.

Cam 10 is fast on total print shaft 12 and cam 11 fast on listing shaft 13.

Whenever a printing operation takes place, shaft 16 is rocked by one or the other of cams 10 or 11 through the instrumentality of lever 55 14 or lever 15. Upstanding arm 18 being fast to shaft 16 is rocked to the right and back to home position during each printing operation whether such operation is brought about by cam 10 or 11.

The shafts 12 and 13 constitute the totaling and listing shafts of a tabulating or record card controlled machine fully disclosed in the Patents 1,822,594 and No. 1,762,145. As 60 fully explained in the patents a series of classified record cards are successively fed to control printing and accumulating elements of the machine. As an incident to feeding a record card the listing shaft 13 is automatically operated setting up the printing elements and effecting the printing operation. 70 When the classification of the records change total shaft 12 is automatically effective to set up the printing elements and effect the printing of a total. Listing shaft 13 is, however, 75 idle during such total printing operations as the total shaft 12 is idle during the listing operation. All the operations are instituted automatically without attention of the operator, once the machine is set into operation. 80 The automatic control is fully explained in the patents referred to. The special automatic paper feeding operation is constructed as follows:

20 is the platen fast on shaft 22. Rotatably mounted on shaft 22 is a sleeve 24 on one end of which is fast a pinion 26, and on the other end a ratchet disc 28 provided in its rim with a single notch 30 (Figs. 1, 2 and 4).

On the outer end of shaft 22 is fast a cross 85 arm 32 on one end of which, at 34, is pivotally mounted a curved pawl arm 36. Arm 36 is equipped on its inner edge with a projecting shoulder 38 held against the rim of disc 28 by spring 40 extending from the free end of 90 arm 36 to the free end of cross arm 32.

Pivotally mounted at 42 on the upper end of arm 18 is a rack member 44. At 42 a slot 95 is provided lengthwise of arm 18 in order that the effective point of connection may be 100

changed, if desired, to adjust the travel of rack 44.

Rack 44 is made in two parts joined by studs 46 slidable in slots 48. The two rack parts 5 are drawn together by spring 50 which forms a resilient connection permitting the length of the rack member to be slightly increased as will appear. Teeth cut in the bottom edge of the rack members engage the teeth of pinion 10 26, being kept in proper mesh therewith by stud 52 held by bracket 54 fast to frame 56 (Fig. 3). Stud 52 is a snug fit in longitudinal slot 58 of the rack 44. Fast on the outer end of rack 44 is a downwardly projecting block 15 60, which cooperates at the proper time with notched collar 62 pinned to platen shaft 22.

With the above construction in mind the operation of the device may be readily understood.

20 While cam 10 is rotating and the type are being positioned by arm 64 (Fig. 1), arm 18 is rocked to the right, drawing with it rack 44, which rotates pinion 26 one complete revolution clockwise.

25 In normal position, shoulder 38 of arm 36 rests in notch 30 of disc 28. Disc 28 is fast to pinion 26 so when the pinion turns one revolution as above disc 28 turns with it, carrying with it arm 36, cross arm 32 and platen 30, which therefore makes one revolution for each revolution of listing cam 10. The above feeding stroke occurs while the type are being positioned prior to the printing operation. While the type are being restored to their 35 normal lowered position after printing, arm 18 rocks to the left causing rack 44 to restore pinion 26 to its normal position by rotating it one complete revolution counterclockwise. During this revolution the platen and its arms 40 32 and 36 stand still, while disc 28 turns backwards until at the end of its revolution shoulder 38 is again resting in notch 30, ready to turn the platen another revolution when the disc is again turned clockwise.

45 This mechanism turns the platen one complete revolution in substantially the same period of time required by the ordinary paper feed devices in turning the platen only one line space, which is only a small fraction of 50 a platen revolution. The platen turns very rapidly and means must be provided at the end of the feeding stroke to stop the platen at a positive position and prevent it overrunning or rebounding, which would cause un- 55 even spacing of the paper.

The positive stopping means comprises notched collar or cam 62, fast on shaft 22, together with block 60, fast on rack 44. Near the end of the feeding stroke the parts are in 60 the position shown in Fig. 5 and are moving in the direction indicated by the arrows. By the time rack 44 has reached the end of its stroke to the right, face 66 of the notch in cam 62 has contacted with the lower surface 65 of block 60 (Fig. 3) thereby positively stop-

ping the rotation of the platen at the desired position, and preventing it from rotating in either direction until block 60 has been moved out of contact with face 66 which occurs on the return stroke of the rack.

The pin, slot and spring connection between the two halves of the rack member 44 obviates the necessity of stopping the travel of arm 18 as accurately as the platen is stopped. Even if the active end of the rack be stopped, the other end and arm 18 may travel further, the two parts of rack 44 being drawn again into normal relationship by spring 50 during the next stroke of the rack to the left.

Thus it will be seen that my invention provides means to positively rotate the platen one complete revolution between succeeding printing operations.

I claim—

1. In a machine of the class described, a platen, a mechanism for effecting printing operations, means operable as an incident to printing operations to automatically rotate said platen a complete revolution in a single continuous operation after printing operations, said means comprising a single notched element, a pawl cooperating therewith and a high ratio driving connection to rotate said notched element and thereby the platen at 90 comparatively high speed with respect to the driving mechanism.

2. In a printing tabulating machine, in combination, a platen, intermittently operable printing mechanism and devices operable as an incident to printing operations, to automatically rotate said platen one revolution between successive printing operations said devices including a single notched element, a pawl cooperating therewith, and means to positively and accurately position said platen at the completion of said revolution.

3. In a printing tabulating machine in combination, a platen, intermittently operable printing mechanism, devices operable as an incident to printing operations to automatically rotate said platen one revolution between successive printing operations and a notched element operable at the end of the platen revolution to interlock said platen and said devices to prevent rotation of said platen.

4. In a printing tabulator, in combination, a platen, intermittently operable printing mechanism, and devices operable to rotate said platen one revolution between successive printing operations, said devices including a rack, an automatically operated arm to actuate said rack, and a resilient connection between said arm and said rack.

5. In a machine of the class described, in combination, a platen printing mechanism operative intermittently by a cam and devices operable by said cam to rotate said platen one revolution between successive printing operations, said devices including an arm rocked

by said cam, a rack reciprocated by said arm and a pinion rotated by said rack.

6. In a machine of the class described, in combination, a platen, printing mechanism operative intermittently by a cam and devices operable by said cam to rotate said devices including a train of mechanism comprising a rack, a pinion operable by said rack and a pawl and ratchet device.

10 7. In a machine of the class described, in combination, a platen printing mechanism operable intermittently, a cam, devices operable by said cam to rotate said platen one revolution between successive printing operations, said devices including an arm rocked by said cam, a rack reciprocated by said arm, resilient means for connecting said rack to said arm, and a device operable to accurately position said platen at the end of its revolution.

15 8. In a machine of the class described, in combination, a platen, and means automatically effective as a result of a printing operation to rotate said platen one revolution in a single operation said means including a driving mechanism including a single notched element and a cooperating pawl and a high ratio driving connection to rotate said platen at comparatively high speed with respect to the driving mechanism.

In testimony whereof I hereto affix my signature.

RALPH E. PAGE.
